UNITED STATES PATENT OFFICE.

ERNEST WILSON CASE, OF SAN DIEGO, CALIFORNIA.

COMBINED LATCH AND LOCK FOR DOORS.

1,073,736.

Specification of Letters Patent. Patented Sept. 23, 1913.

Application filed April 11, 1913. Serial No. 760,423.

To all whom it may concern:

Be it known that I, ERNEST W. CASE, a citizen of the United States, residing at San Diego, county of San Diego, and State of California, have invented certain new and useful Improvements in Combined Latches and Locks for Doors, of which the following is a specification.

This invention relates to combined latches and locks for doors.

The present invention has for its object the provision of an improved latch and lock for doors, particularly adapted for use on screen doors, which will be self-latching when the door is closed and will hold it against accidental unlatching, but will be adapted for disengagement when pressure is applied to the door, and to combine therewith novel means, whereby the door may be readily locked.

The present invention is distinguished from those combined latches and locks heretofore known in that it is so constructed that the parts thereof are reversible and do not require previous calculation as to their exact position; further, in the particular construction of the parts; still further in the improved manner in which the parts are adapted to coöperate with each other.

The invention is also distinguished from earlier devices in that the parts are made, respectively, in one piece, thus greatly simplifying and cheapening, as well as strengthening, them.

The embodiment of the invention herein-after described and which is shown in the accompanying drawings is susceptible of changes in detail without departing from the spirit and scope of the improvement.

In the accompanying drawings:—Figure 1 is a perspective showing the invention in use, the parts being locked; Fig. 2, a view showing the parts in position for engagement; Fig. 3, a section through the combination plate latch and lock; Fig. 4, a side elevation of the keeper; and Fig. 5, a bottom view thereof.

The combined latch and lock consists of three parts, the catch 1, the keeper 2 and the locking member 3.

The catch 1 may be made from a single piece of metal, bent or cast, having the base 4, the substantially cylindrical head 5 arranged transversely of the base, and the neck 6 which has the notches or recesses 7 in its opposite edges, said notches or recesses

being similar. The neck may also be provided with rabbeted parts 8 to accommodate the thickness of the base of the keeper. The base has suitable openings for the reception of screws and it is intended to be attached to the door, but the arrangement of the parts may be reversed.

The keeper has a base 9 provided with openings for the passage of screws or other fastenings to connect it to the door frame or jamb and it is formed integral, by casting or bending, with a flange 10 having lips 11 disposed inwardly over the base and separated therefrom at 12 in order that they may have a certain degree of springiness or resiliency to carry out their function of engaging the cylindrical head 5. The faces 13 are beveled or rounded so that the cylindrical head 5 will be guided into the space between the termini of said lips. After the head has snapped past the termini of the lips, it is securely held, as shown in Fig. 1, but the door can be readily opened by the application of pressure, as the rounded or cylindrical construction of the head 5 permits it to be readily withdrawn from between said lips. The engagement of the lips with the head, however, latches the door against any accidental opening.

The base of the keeper is provided with a bearing 14 for a locking loop or bail 15 which is adapted to be swung over and engaged with the uppermost notch 7 whenever it is desired to lock the door. At all times the locking bail is thrown back and out of the way. Its hinged engagement with the bearing 14 is such that the latch is frictionally held wherever positioned so that it will not accidentally be jarred into engagement with the head of the catch.

Both the keeper and the catch can be used either "right" or "left", thus adapting the device to a door regardless of the direction in which it opens. The provision of the notches 7 on both sides of the neck of the catch insures one of said notches being in position for engagement by the locking bail, regardless of the position of the parts.

Having thus described my invention, what I claim as new and desire to secure by Letters Patent, is:—

1. A combined latch and lock having, in combination, a catch consisting of a base, a neck having notches on opposite sides, and a head, a keeper having lips adapted to engage said head, and a swinging lock mount-

ed on the keeper and adapted to engage the outermost of the notches aforesaid.

2. A combined latch and lock having, in combination, a one-piece reversible catch composed of a base, a neck having notches on opposite sides, and a rounded head, a keeper having a one-piece base, a flange, and springy converging lips, and a locking loop or bail hinged to the base of the keeper and

adapted to engage whichever of said notches is outermost aforesaid.

In testimony whereof, I hereunto affix my signature in presence of two witnesses.

ERNEST WILSON CASE.
